(57) **CLAIM**

We claim the ornamental design for an elastomeric resilient handle sleeve, as shown and described.

DESCRIPTION

FIG. 1 is a front, right side, perspective view of an elastomeric resilient handle sleeve showing our new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

1 Claim, 4 Drawing Sheets
